UNITED STATES PATENT OFFICE.

ROBERT R. WEAVER, OF COLUMBUS, OHIO.

UNCOUPLING DEVICE FOR CAR-COUPLEINGS.

1,136,068.

Specification of Letters Patent. Patented Apr. 20, 1915.

Application filed February 16, 1914. Serial No. 819,051.

To all whom it may concern:

Be it known that I, ROBERT R. WEAVER, a resident of Columbus, in the county of Franklin and State of Ohio, have invented 5 certain new and useful Improvements in Uncoupling Devices for Car-Couplings; and I do hereby declare the following to be a full, clear, and exact description of the invention, such as will enable others skilled 10 in the art to which it appertains to make and use the same.

This invention relates to improvements in uncoupling devices for car couplings,—the object of the invention being to provide 15 simple and efficient devices for the raising of the locking pin or block of a car coupling, which shall be so operable from the side of a car and so constructed and arranged that the hand-operated portion must be lifted for 20 actuating the pin lifting member; and thus obviate danger of accidental operation which might occur were that portion to which power is to be applied arranged to be depressed or moved downwardly for actuating the pin or block lifting member.

With this object in view the invention consists in certain novel features of construction and combinations of parts as herein-after set forth and pointed out in the claim.

30 In the accompanying drawings, Figure 1 is a perspective view illustrating an embodiment of my invention, and Fig. 2 is a view showing a modification of the same.

1 represents the end sill of a car and 2 35 illustrates a portion of a car coupling provided with a locking block or pin 3 having a loop or eye 4 at one end.

A plate 5, provided with a boss 6, is rigidly secured to the end sill 1, and to said 40 boss, one end of a lever 7 is pivotally attached. This lever is disposed approximately parallel with the end sill and its contracted free end portion 8 passes freely through the eye or loop 4 of the locking pin 45 or block 3,—the free extremity of the portion 8 of lever 7 being preferably, made hook-shaped as indicated at 9. At a point between the pivotal connection of the lever 7 with the end sill and the coupling 2, one 50 end of a hand lever 10 is pivotally supported by the end sill, a boss 11 being provided on the end sill to facilitate pivotal connection of said hand lever to the end sill. A clip or

loop 12 (inverted U-shaped in vertical section) is secured at its lower end to the hand 55 lever 10 and embraces the lever 7 at a point between the pivotal connections of the two levers to the end sill. A bolt 13 passes transversely through the loop or clip 12 in such position as to be disposed under the 60 lever 7 so that said lever may rest and move thereon. The hand lever 10 is made of such length that its hand-engaging portion shall be within convenient reach of a trainman 65 at the side of the car.

When it is desired to raise the locking pin or block, the trainman will raise the free or hand-engaging end of the lever 10, and this movement will be transmitted by the loop or clip 12 and bolt 13 to the lever 7 to raise 70 the latter on its pivotal support and thus cause the free end portion of said lever 7 to lift the locking pin. By so constructing the devices that the hand lever must be raised to actuate the pin lifting lever, the train- 75 man would fall away from the car in the event of breakage of some part of the mechanism, and furthermore, there will be no danger of accidental operation of the uncoupling mechanism, as might occur with 80 constructions in which downward hand or foot pressure on the actuating lever will cause the locking pin to be raised.

In the form of the invention shown in Fig. 2, the loop or clip 12 is omitted and the 85 hand lever 10 is bent to form a shoulder 14 disposed under and engaging the lower edge of the lever 7 at a point between the pivotal connections of the two levers to the end sill.

Other slight changes might be made in 90 the details of construction of my invention without departing from the spirit thereof or limiting its scope and hence I do not wish to restrict myself to the precise details herein set forth.

Having fully described my invention what I claim as new and desire to secure by Letters-Patent, is:—

In uncoupling devices for car couplings, the combination with an end sill, and a car 100 coupling provided with a locking pin, of a pin-raising lever pivoted at one end to the end sill, an operating lever pivoted to the end sill between the ends of said pin-raising lever and extending laterally past 105 the pivoted end of the latter, a clip secured

to the operating lever and embracing the pin-raising lever between the pivotal connections of said levers to the end sill, and a part carried by said clip and engaging the pin-raising lever to raise the latter when the operating lever is raised.

In testimony whereof, I have signed this

specification in the presence of two subscribing witnesses.

ROBERT R. WEAVER.
